UNITED STATES PATENT OFFICE.

PAUL McMICHAEL, OF FLUSHING, NEW YORK, ASSIGNOR TO HYDROCARBON REFINING PROCESS COMPANY INC., OF NEW YORK, N. Y., A CORPORATION OF NEW YORK.

REFINING OF PETROLEUM OILS AND DISTILLATES.

No Drawing.

Application filed January 11, 1924. Serial No. 685,703.

This invention relates to an improved method for refining petroleum hydrocarbons, and more particularly relates to a method for refining light petroleum oils and distillates, especially gasoline-containing cracked oils and pressure distillates.

Light petroleum distillates, particularly those intended for use in automobile internal combustion engines, should be of good color, free from objectionable odors, substantially free from sulphur, and free from gum and resin forming constituents. Cracked distillates usually contain a reduced amount of sulphur and an increased amount of unsaturated material. The formation of gummy and resinous masses on standing, and the instability of certain oils to prolonged exposure to light, are largely due to the presence in the oil of unsaturated material such as terpenes, diolefines, and isomers, polymers and homologues or derivatives thereof. All unsaturated compounds, however, are not objectionable in these respects, and some unsaturated compounds, such as the olefines, constitute an excellent and advantageous constituent for motor fuel, and their removal constitutes an unnecessary loss. Sulphur compounds and gum forming compounds are particularly objectionable in oils intended for use in internal combustion engines because they tend to form gummy deposits in various parts of the engine and to form corrosive combustion products.

Hitherto, the general practice in the refining of such oils has involved initial treatment with sulphuric acid, and the reaction products of such initial treatment are of such character as to entail the use of strong sulphuric acid for removing them. Treatment with strong sulphuric acid substantially denudes the oil of any olefines and similar unsaturated compounds it may have contained prior to the treatment and tends to introduce sulphur into the oil in the form of alkyl sulphates. Refining methods have also been proposed involving initial treatment of the oil with quite dilute sulphuric acid, but such methods, if carried out in a manner to avoid destruction or removal of the olefines and similar compounds, do not produce a stable product of good color and odor and free from gum and resin forming bodies. Another disadvantage of those previous methods of refining with sulphuric

acid which have been found commercially useful has been the number of distillations involved.

According to the present invention, the oil to be refined is subjected to an initial treatment with an aqueous solution of an alkali or an alkali earth at ordinary temperatures. Following the alkaline treatment, the oil is subjected to a regulated treatment with relatively dilute sulphuric acid. After the acid treatment, the oil is subjected to a further alkaline treatment at ordinary temperature, or to a distillation in the presence of an alkali or an alkali earth or a solution thereof, or to a combination of these two latter treatments. The oil may be washed following the initial alkaline treatment and the acid treatment, and treatment with a comminuted solid decolorizing agent may be employed following the final alkaline treatment.

The initial alkaline treatment removes some sulphur compounds and apparently assists in the subsequent removal of other sulphur compounds by modifying them to a less refractory form and also appears to assist in the removal of gum forming material. When first subjected to treatment with an alkali, difficultly removable objectionable compounds necessitating the use of strong acid are not introduced into the oil and components tending to form such objectionable compounds upon treatment with sulphuric acid are largely eliminated. In conjunction with the preliminary alkaline treatment, the rigor of the subsequent sulphuric acid treatment can be reduced sufficiently to prevent formation of oil-soluble alkyl sulphates and to substantially avoid removal of olefines and similar desirable unsaturated compounds, while, at the same time, sulphur compounds and gum forming compounds can be substantially completely removed or converted to a form readily removed with a light alkaline treatment or simple steam distillation. The chemical treatments are carried out at ordinary temperature, reducing evaporation losses, and the small number of operations reduces mechanical losses. A single distillation is usually sufficient, if any distillation is required, to produce a completely refined oil. The refined product of the invention is of good color and odor, substantially free from sulphur compounds and gum and resin form-

ing compounds, and retains practically all of the olefines and similar desirable unsaturated compounds. The odor of the refined product of the invention somewhat suggests the presence of monohydric alcohols.

- Advantageously, the initial alkaline treatment is effected with a strongly caustic solution, for example, with a solution of caustic soda corresponding to a concentration having a specific gravity equal to about 38° to 40° Bé. The oil and the alkaline solution are thoroughly mixed and agitated together. Intermittent agitation, for example, may be employed over a period of from 1 to 4 hours, depending upon the concentration of the alkaline solution and the composition of the distillate under treatment. After this treatment, the oil and the alkaline solution may be separated by permitting the mixture to stand and withdrawing either the alkaline solution or the oil, and the separated oil thoroughly washed with water to remove any excess caustic. The oil and wash water may be separated by settling.
- Sulphuric acid of a concentration between about 70% and 83% will remove diolefines, terpenes and similar gum forming compounds, or will convert them to a form capable of removal by subsequent alkaline treatment, but acts very slowly, if at all, upon unsaturated compounds such as the olefines. Following the initial alkaline treatment, the oil is agitated with such relatively dilute sulfuric acid over a period sufficient to remove the gum and resin forming constituents without effecting material loss due to destruction or removal of unobjectionable unsaturated compounds. The total amount of sulfuric acid employed and the total time of agitation of the oil with the sulfuric acid depends upon the degree of concentration of the acid employed and the composition of the oil being treated. Advantageously, the total quantity of acid may be divided into several portions and the oil treated successively with these several portions. Using from 1.5% to 15% of the weight of the oil of sulphuric acid of a specific gravity of 60° Bé., the total time of agitation may aggregate from 1 to 4 hours. Following separation of the oil and acid after acid treatment, the oil may be washed with water to remove excess acid and this wash may be supplemented with a mild alkaline wash to complete the removal of acid.
- Further treatment following the acid treatment depends to a large extent upon the boiling range and the character of the oil being refined and of the product desired. Some oils, particularly among those that distill substantially completely below about 225° C., can be completely refined by final treatment with an alkaline solution at ordinary temperature. Such oils are treated with a solution of an alkali or an al-

kali earth for a period for example, of from 30 minutes to 1 hour, the mixture allowed to settle to effect separation of the oil and alkaline solution, and the solution or oil drawn off. In some cases, even though the final alkaline treatment at ordinary temperature is not sufficient, such lower boiling oils can be completely refined with the production of a satisfactory product without distillation by subjecting the oil after this alkaline treatment to treatment with a comminuted solid decolorizing agent, such as infusorial earth, activated carbon, silica gel, boneblack or fuller's earth. The oil may be filtered through the decolorizing agent or a small amount of the decolorizing agent may be agitated with the oil and subsequently separated by filtration.

Where distillation is necessary to complete the refining, the procedure is determined in part by the boiling range of the original fraction submitted to treatment and the desired boiling range of the completely refined product. Assuming that 225° C. is approximately the end-boiling point desired in the final product, if the major portion of the oil distills below about 225° C., for example more than about 75%, the entire fraction is advantageously submitted to distillation in the presence of a fixed alkali, that is of an alkali or an alkali earth, and the fraction constituting the desired final product separately collected. Distillation may be continued and the remaining oil collected as a separate fraction. This secondary product is frequently discolored, shading from a light yellow to a brown, but it is substantially free from gum or resin forming compounds and from sulfur, has a good odor and contains substantially all of the olefines and such unobjectionable unsaturated components as were contained in the original oil within this boiling range.

If a large part of the original oil boils above 225° C., the assumed desired end-boiling point, it is frequently more advantageous from the standpoint of economy to separate a fraction having the desired boiling range prior to the refining operation. This method of procedure eliminates unnecessary consumption of caustic and acid in treating that part of the oil which is not within the boiling range of the desired final product. The additional initial distillation is preferable if it is more economical than the additional amount of acid and caustic required to treat the entire fraction. The boiling range of the oil being treated, before or at any time during treatment, can be readily determined by the fractional distillation of a small sample.

Any saponifiable compounds contained in the original oil are removed in the form of soap by the initial alkaline treatment whereas they are usually decomposed if subjected

to initial acid treatment. These compounds can be recovered by acidulation of the soap formed by the initial alkaline treatment. Terpenes, diolefines and other gum and resin forming bodies removed with the sulphuric acid, can, to a large extent, be recovered from the acid sludge by dilution of this sludge with water.

The following specific example will serve to further illustrate the invention, although it will be understood that the invention is not in any way limited thereby. A pressure distillate having an iodine absorption number of 26.6, a sulfur content of 0.152% by weight, and a gum content of 0.4212 grams per hundred c. c. measured at 15° C., was agitated for approximately one hour at ordinary temperature (about 15° C.) with 2.5% by volume of a 40° Bé. water solution of sodium hydroxide and after separation of the oil and alkali by settling was washed with approximately 5% by volume of water to remove excess alkali. The loss during this step was about 1.2% by volume. The oil was then agitated for a total time of approximately 1 hour at ordinary temperature with a total of about 2.5% by volume of 60° Bé. sulphuric acid. The acid was applied in three successive portions of about 0.5%, 1%, and 1% respectively. The oil and acid were separated after each treatment and after the last acid treatment the oil was washed with approximately 5% by volume of water to remove excess acid. The loss during this step was about 1.5% by volume on the original distillate treated. The partially refined oil then had an iodine absorption number of 24.9, a sulphur content of 0.012% by weight, and a gum content of 0.023 grams per hundred c. c. measured at 15° C. The separated oil was then distilled with steam in the presence of about an equal volume of a saturated water solution of hydrate of lime. The distillate was collected in two fractions, the first amounting to about 82.7% by volume of the original distillate and the second to about 14.6%. The first fraction constituted a completely refined product, was water white, had a distinctly agreeable odor, an iodine absorption number of 25.5, contained only a trace of sulphur, and had a gum content of 0.0008 grams per hundred c. c. measured at 15° C.

It will thus be seen that the present invention provides an improved method of refining hydrocarbon oils and distillates which involves a minimum of evaporation and mechanical losses during chemical treatment and which also eliminates unnecessary distillation. It will also be seen that this invention eliminates unnecessary loss due to the destruction or removal of desirable

unsaturated compounds such as olefines during the refining operation and permits retention in the refined product of substantially all of the olefines and similar unsaturated constituents boiling within the range of the refined product that were contained in the original oil treated.

I claim:

1. A process of refining petroleum oils and distillates boiling substantially completely below about 225° C., which comprises agitating the oil with a solution of an alkali, thereafter subjecting the oil to treatment with from about 1.5% to 15% of sulphuric acid of a concentration between about 70% and 83% H_2SO_4 , and subsequently steam distilling the separated oil in the presence of a fixed alkali.

2. A process of refining petroleum oils and distillates boiling substantially completely below about 225° C., which comprises agitating the oil with a solution of an alkali, thereafter subjecting the oil to treatment with from about 1.5% to 15% of sulphuric acid of a concentration between about 70% and 83% H_2SO_4 , thereafter steam distilling the separated oil in the presence of a fixed alkali and subsequently treating the oil with a comminuted solid decolorizing agent.

3. A method of refining petroleum oils and distillates, which comprises agitating the oil with a solution of an alkali, separating the oil from the alkaline solution and agitating the separated oil with dilute sulphuric acid, separating the oil from the acid sludge and steam distilling the separated oil in the presence of a fixed alkali, and separately collecting the fraction of the desired boiling range.

4. A method of refining petroleum oils and distillates, which comprises subjecting the oil to treatment with a solution of an alkali, separating the oil from the alkaline solution and treating the separated oil with sulphuric acid of a concentration between about 70% and 83% H_2SO_4 , separating the oil from the acid sludge and distilling the separated oil with steam in the presence of a fixed alkali and, separately collecting the fraction of the desired boiling range.

5. The method of refining petroleum oils and distillates, which comprises subjecting the oil to treatment with a solution of an alkali, separating the oil from the alkaline solution and treating the separated oil with sulfuric acid of a concentration between about 70% and 83% H_2SO_4 , separating the oil from the acid sludge and steam distilling the separated oil in the presence of a fixed alkali.

In testimony whereof I affix my signature.
